UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

MUSICAL INSTRUMENT.

1,301,062.

Specification of Letters Patent. Patented Apr. 15, 1919.

Application filed March 18, 1918. Serial No. 223,116.

To all whom it may concern:

Be it known that I, WALTER I. KIRK, a citizen of the United States, residing at Chicago, in the county of Cook and State of Illinois, have invented a certain new and useful Improvement in Musical Instruments, of which the following is a full, clear, concise, and exact description, reference being had to the accompanying drawings, forming 10 a part of this specification.

My invention relates to musical instruments, and especially to harps or the like.

One of the objects of the invention is to provide means whereby a musical instrument 15 may be tuned without requiring the use of the separate tuning device.

Another object of the invention is to conceal such means so that to all intents and purposes the musical instrument may appear 20 to be in the ordinary or usual form.

Another object of the invention is to provide means whereby a harp may be provided with an arrangement by which it may be tuned without the use of a separate tuning 25 instrument; and also to conceal such arrangement so that the harp may appear from the outside to all intents and purposes as the usual form of harp.

A further object of the invention is to provide 30 a new, novel, and advantageous construction of tuning device.

A still further object of the invention is to provide a construction of tuning device which may be readily applied to a harp or 35 other musical instrument, and which is particularly adapted to be located and secured in a concealed position in a musical instrument or elsewhere and operated by the player thereof.

40 In the accompanying drawings, Figure 1 is a side elevation of a harp embodying my present invention;

Fig. 2 is a view of the inside of the body, with the sounding board removed; and 45 Fig. 3 is a vertical section taken on line 3-3 in Fig. 2.

Referring to the drawings, and especially to Fig. 1, I show the usual form of harp having a body 1, pillar 2, and neck 3. The 50 body 1 is of a somewhat concave cross section and is shown provided with longitudinally extending openings 4-4. Within this body 1 I show a tuning fork device which is best shown by itself in Fig. 3. This device 55 consists of a metallic tubular member 5

which is preferably rectangular in form, although it may be of different cross sectional shapes. This tubular member 5 is intended for use as a resonator and is closed throughout except for an opening 6 in its upper end. 60 Above the tubular resonator 5 is a tuning fork 7 which is arranged lengthwise of the resonator 5 with the two ends or prongs adjacent to the upper end of the member 5 and to the aperture 6 therein. A striker 8 65 is arranged to strike one of the prongs 7a. This striker 8 is preferably mounted upon a swinging member 9 which is pivoted at 10 and has an extension 11 so that said member 9 may be swung back and forth to cause the 70 striker 8 to act against adjacent prong 7a and thereby operate the tuning fork.

As a matter of further and specific improvement I arrange to mount all of the above parts and secure the same in position 75 by means of a strap 12 having a portion 12a which may be and is secured to the inner wall of the body 1 by means of screws 13-13, said strap 12 also having a portion 12b to which the resonator 5 is secured as 80 by brazing or otherwise. This strap 12 also has a cross portion 12c to which the upper end of the tuning fork 7 is secured, as for example by means of a screw portion 15 passing through said part 12c and being provided with set nuts 16 and 17. A further portion 12d of said strap 12 extends upwardly from the portion 12c and supports the pivot 10 upon which the swinging member 9 is pivoted. A bumper 18 is preferably 85 mounted on the swinging member 9 and is arranged to strike against a buffer or abutment 19 on the strap portion 12d, the buffer 19 being desirably provided with a strip 20 of felt for softening or deadening the blow. 90 A coiled spring 21 is preferably mounted upon the pivot 10 and arranged to act against the extension 11 of the swinging member 9 in such a way as to cause the member 9 to swing toward the prong 7a. 95 Thus an actuation of the extension 11 to the left as shown by the arrow in Fig. 3 would cause the member 9 to swing the striker 8 away from the adjacent prong 7a and the release of said extension 11 would permit the 100 spring 21 to swing the member 9 back toward the prong 7a, as a result of which the striker 8 would strike the prong 7a and cause the operation of the tuning fork.

Thus an operator of the harp may put his 110

finger or hand through one of the apertures 4 while he is still sitting at the harp and may draw the extension 11 toward him to cause the member 9 to swing away from the tuning fork and may thereupon release said member 11 to permit the member 9 to swing to the tuning fork 7 and strike the same. Thus while sitting at the harp the operator may actuate the tuning fork and 10 may do this repeatedly as often as desired to tune his instrument.

It will be seen that the tuning fork instrument is entirely concealed and will not be visible without close inspection of the instrument from the exterior of the same. Also that the presence of the tuning fork makes unnecessary a separate tuning fork instrument and permits the harp operator or player to tune his instrument without the 20 need of any separate or other device, the tuning fork and harp being to all intents and purposes a single instrument.

It will be understood that such a tuning fork arrangement may be applied to musical instruments other than harps and also that the character or construction of the tuning fork device may be different from that herein shown while still embodying the broader features of the invention, and that the location of the tuning fork device relatively to the musical instrument may be varied. It will also be seen that the particular construction of tuning fork device herein disclosed may be used for other purposes than in connection with a musical instrument, being capable of use by itself, although it is particularly well adapted for use in the manner shown or in other ways where it is desired to secure such a device upon a wall or support.

It will be understood that changes and modifications may be made without departing from the spirit of the invention.

What I claim is:

- 45 1. A harp having a hollow body provided with an aperture and a tuning fork device located within the hollow body and having a striker arranged adjacent to said aperture.
2. A harp having a hollow body provided 50 with an aperture and a tuning fork device located within the hollow body and having

a striker arranged adjacent to said aperture, said tuning fork device comprising a resonator secured to the wall of the harp body and a tuning fork located above said resonator and in position to be actuated by said striker.

3. A tuning fork device comprising a tubular resonator having an aperture at its upper end, a metal strap secured to the side of said resonator and extending upwardly from the same, and a tuning fork secured to said strap and extending down to the resonator so that its prongs are adjacent to the aperture therein. 60

4. A tuning fork device comprising a tubular resonator having an aperture at its upper end, a metal strap secured to the side of said resonator and extending upwardly from the same, and a tuning fork secured to said strap and extending down to the resonator so that its prongs are adjacent to the aperture therein, and a striker extending lengthwise of said fork and pivoted near the upper end to the same. 65

5. A tuning fork device comprising a tubular resonator having an aperture at its upper end, a metal strap secured to the side of said resonator and extending upwardly from the same, and a tuning fork secured to said strap and extending down to the resonator so that its prongs are adjacent to the aperture therein, and a spring controlled striker extending lengthwise of said fork and pivoted near the upper end to the same. 80

6. A tuning fork device comprising a tubular resonator having an aperture at its upper end, a metal strap secured to the side of said resonator and extending upwardly from the same, and a tuning fork secured to said strap and extending down to the resonator so that its prongs are adjacent to the aperture therein, and a spring controlled striker extending lengthwise of said fork and pivoted near the upper end to the same, 90 said striker being pivoted upon an end portion of said strap.

In witness whereof, I hereunto subscribe my name this 12th day of February, A. D. 1918.

WALTER I. KIRK.
